UNITED STATES PATENT OFFICE.

JOHN MONTGOMERY COLLINS, OF GLASGOW, SCOTLAND.

MACHINERY FOR CLEANING OR RENOVATING CARPETS, RUGS, AND SUCH LIKE.

No. 826,017.

Specification of Letters Patent.

Patented July 17, 1906.

Application filed September 12, 1904. Serial No. 224,094.

To all whom it may concern:

Be it known that I, JOHN MONTGOMERY COLLINS, engineer, a subject of the King of Great Britain, residing at 121 Swanston street, 5 Bridgeton, Glasgow, Scotland, have invented certain new and useful Improvements in Machinery for Cleaning or Renovating Carpets, Rugs, and such Like, of which the following is a specification.

This invention relates to machinery for cleaning or renovating carpets, rugs, and such like; and it has for its object to improve the construction of such machinery.

In carrying out my invention I use a roller or cylinder, over which the carpet or such like is passed, and this roller, which is carried in suitable frames, is driven by worm or other gear from a power-shaft. By means of a suitable arrangement the roller can be raised or lowered to suit the nature of the material being treated. The surface of the roller is roughened, so as to grip and feed the cloth, and above it is arranged a revolving brush, which has a lateral or reciprocating motion imparted to it. The mechanism for driving this brush is or may be such that its direction of revolution is reversed at intervals. Benzin, ammonia, or other suitable detergent is fed, by means of a spray-pipe, (or pipes,) to a feeding-cover arranged over the brush and adapted to deliver the benzin thereto.

In order that my invention may be clearly understood, I have hereunto annexed two explanatory sheets of drawings, showing a convenient method of constructing the machine.

Figure 1 is an end elevation, Fig. 2 a side elevation, and Fig. 3 a plan, of the machine. Fig. 4 is a vertical section. Figs. 5 and 6 are 40 sectional views of parts of the brush and its shaft.

a is the feed-roller, over which the carpet or the like is passed, and this roller has journals at its ends, which are carried in bearing-blocks capable of sliding in vertical slots *b* in the end frames *c*. The roller can be raised and lowered to suit the material being treated by means of vertical screw-spindles *d*, whose screws work in the bearing-blocks 45 aforesaid. These spindles *d* can be rotated when desired, so as to effect the adjustment of the roller, by means of worm-gear *e*, driven by the shaft *f*, which latter can be turned by the hand-wheel *g*. The feed-roller 50 is rotated by means of worm-gear *h* *i* *h'* *i'*, driven from the counter-shaft *j*, which latter

is driven by the bevel-gear *k* from the main shaft *l*. *m* represents belt-pulleys for driving the shaft *l*.

n is the rotary brush, whose shaft *p* is carried in the bearings *o* on the end frames. The shaft, which is rotated by means of a chain-gear *p'* *q* from the main shaft *l*, has its ends carried out beyond the bearings for a short distance, as shown, and connected to rectangular blocks *r*, which slide in guideways *p*⁴ *p*⁴. Each slide-block is reciprocated laterally on its guideways by means of a lever *s*, which at its upper end is passed through a hole in rock-bar *s'*, fitted to the block. The lever *s* is pivoted at *s*² to the bracket *t*, depending from the guideways, and its lower end is connected by the rod *u* to a crank *v* on a cross-shaft *w*, actuated by means of the bevel-gear *x* from the shaft *l*. The mechanism for effecting the reciprocation is the same at each end of the machine. The brush-shaft *p* has a feather *p*² on it which can slide in a keyway in the hub of the chain-wheel *p'*, which latter is fitted loosely on the shaft and is prevented from moving laterally by a fixed bracket *p*³ bearing against its hub.

Each end of the shaft is connected to its slide-block *r* by means of a loose collar *y*, having laterally-projecting pins *y'*, which rest in the recesses *y*² of the block. The collar *y* rests between the fixed collars *y*³ of the shaft.

The cover *z* for the liquid detergent is made of metal and in two portions 1 2, which are hinged to one another and to a longitudinal fixed rod 3, which extends from the one end frame of the machine to the other at a point above the brush. Each portion of the cover is made of a somewhat curved shape, as shown at Fig. 4, and the whole cover hangs 95 over the top of the brush, the hinged portions being held outward and away from the brush by means of chains *z'* passing over guide-pulleys carried on the roof of the building and provided at their ends with counter-balance-weights *w'*. The attendant by manipulating these chains can raise up and lower down the portions of the cover, as desired. The liquid detergent is forced or otherwise supplied to overhead pipes *z*², with 105 which flexible pipes *z*³ connect. These pipes *z*³ conduct the detergent to pipes *z*⁴, arranged within the cover and which are perforated, so as to deliver sprays against the sides of the cover. The detergent runs down the sides of 110 the cover and into the depressions or troughs 4 at the bottom and then flows onto the brush

as the latter revolves. It will be seen that the edges 5 of the depressions are rounded. This is to prevent the bristles of the brush, no matter which way it is turned, catching 5 on the edges.

The cover is made in a number of sections, each with its pipes complete, so that any one or more of the sections can be put into or out of operation, as desired. Cocks or other 10 means would of course be provided for cutting off the supply of liquid detergent from any section.

The brush is also preferably made in a number of sections. To do this, there are a number of cylindrical stocks n' (see Fig. 6) slipped 15 on the shaft p , and these stocks are made in halves, which are held on the shaft and to each other by means of rings n^2 , which lie in the grooves formed by the abutting recesses 20 n^3 at the ends of the stocks. The stocks are held pressed against one another by means of nuts and collars at the ends of the shaft. With this arrangement any one or more of 25 the sections when worn can be removed and replaced by a new one.

Having now fully described my invention, what I claim, and desire to secure by Letters Patent, is—

1. A carpet cleaning or renovating machine comprising, in combination, a frame 30 with guide thereon, a roller, means for revolving the roller, a cylindrical brush mounted on a shaft, a sliding shoe connected to one end of the shaft and working on said guide, 35 means for reciprocating the shoe, and means for rotating the brush.

2. A carpet cleaning or renovating machine comprising, in combination, a frame

with guides at each end thereof, a roller, means for revolving the roller, a cylindrical 40 brush mounted on a shaft, sliding shoes connected to each end of the shaft and working on said guides, means for reciprocating the shoes, and means for rotating the brush.

3. A carpet cleaning or renovating machine comprising, in combination, a frame, a 45 roller, means for revolving the roller, a cylindrical brush mounted on a shaft carried by the frame, sliding shoes connected to each end of the shaft, guides for the shoes, levers 50 connected with the shoes, connecting-rods jointed to the levers, crank-shafts to which said connecting-rods are connected, and means for operating said crank-shafts.

4. A carpet cleaning or renovating machine comprising, in combination, a frame, a 55 roller, means for revolving the roller, a cylindrical brush mounted in the frame, horizontal guides projecting from each end of the frame in line with the brush, sliding shoes on 60 the guides, a cylindrical brush mounted on a shaft whose ends project out over the guides, loose collars on the ends of the shaft, pins on the collars adapted to engage with the shoes, a feather on the shaft, a wheel for rotating 65 the shaft said wheel having a feather-way in its hub for the reception of the said feather, means for rotating the wheel and means for reciprocating the shoes.

Signed at Glasgow, Scotland, this 3d day 70 of September, 1904.

JOHN MONTGOMERY COLLINS.
